United States Patent

Des. 240,815

Patented Aug. 3, 1976

240,815

COIN DISPLAY PAGE

Everett A. Peterson, 113 St. Marks Place,
Roslyn Heights, N.Y. 11577

Filed Jan. 11, 1974, Ser. No. 432,698

Term of patent 14 years

Int. Cl. D19—04

U.S. Cl. D19—33

FIG. 1 is a perspective view of a coin display page showing my new design;

FIG. 2 is a rear elevational view; and

FIG. 3 is a top edge view.

I claim:

The ornamental design for a coin display page, as shown.
